TYPEWRITING MACHINE

Emerson W. Gifford, Teaneck, N. J., assignor to
 International Business Machines Corporation,
 New York, N. Y., a corporation of New York

Application December 17, 1938, Serial No. 246,264

26 Claims. (Cl. 197—179)

This invention relates to typewriting machines and has reference to improvements in the tabulating mechanism.

An object of the present invention is to im-

prove tabulating mechanisms of the type where-
 in there is usually provided a column stop for
 each space and a key which is operable to set
 the stops to active position. A tabulating mech-
 anism of this type is disclosed in application
 10 Serial No. 41,021, filed September 18, 1935, by
 C. W. Crumrine, now Patent No. 2,157,053. The
 present application relates to an improvement
 in the means for setting the stops in the afore-
 said Crumrine application.

15 An object of the present invention is to pro-
 vide a means whereby damage to the column
 stops is prevented in case the carriage is moved
 while the stop setting key is being depressed.

An object is to provide a means for positively
 20 withdrawing from between the unset stops the
 member which coacts directly with the stops to
 move them to active position.

An object is to provide means responsive to
 movement of the carriage for positively with-
 25 drawing from between the unset stops the mem-
 ber which projects the stops to active position.

An object is to provide means whereby the
 movement of the carriage is utilized to control
 the retraction of the stop setting member from
 30 between the stops in case the carriage is moved
 while the stop setting key is held depressed.

Further objects of the instant invention reside
 in any novel feature of construction present in
 the embodiment of the invention described and
 35 shown in the accompanying drawings, whether
 within or without the scope of the appended
 claims and irrespective of other specific state-
 ments as to the scope of the invention contained
 herein.

40 In the drawings:

Fig. 1 is a vertical section of a typewriter em-
 bodying the present invention.

Fig. 2 is a plan view of the tabulating mech-
 anism and the stop setting mechanisms.

45 Fig. 3 is a large scale plan view of certa'n por-
 tions of the tabulating mechanism and stop set-
 ting mechanism appearing in Fig. 2.

Fig. 4 is a vertical section on the line 4—4
 Fig. 3.

50 Fig. 5 is a view similar to Fig. 3, but shows the
 position of the stop setting head after the car-
 riage has been moved a predetermined amount
 while the stop setting key is held depressed.

Fig. 6 is a view similar to Fig. 3, but shows a
 55 modified form of the invention wherein the stop

setting head is positively retracted in response
 to movement of the carriage.

Fig. 7 is a vertical section on the line 7—7
 in Fig. 6.

Fig. 8 is a vertical section on the line 8—8 in 5
 Fig. 7.

The present invention has been shown in the
 drawings as applied to the well known "Interna-
 tional" electric writing machine, formerly known
 as the "Electromatic," which now is equipped 10
 with the key set stop mechanism disclosed in
 the aforesaid Crumrine application. This stop
 setting mechanism has been in commercial use
 for a number of years and is now well known in
 the art. Notwithstanding the selection of the 15
 specific machine and stop setting mechanism
 disclosed in the above application for the pur-
 pose of description, the present invention may
 be employed in any machine in which the column
 stops are set by means of a key or similar ele- 20
 ment, whether such machine is operated by
 power or by hand.

In Fig. 1 only such portions of the machine as
 are necessary to an understanding of the present
 invention have been shown. The reference nu- 25
 meral 10 generally designates the carriage on
 which is rotatably mounted the usual platen 11.
 The carriage is slidably mounted on front rail
 12 and rear rail 13 by means of suitable anti-
 friction bearings in a well known way. The car- 30
 riage is driven in a letter spacing direction by
 the usual spring drum, generally designated 13,
 which is connected to the carriage by means of
 a flexible tape 14. The carriage is provided with
 a stop bar 15 on which are rotatably mounted 35
 the column stops 16.

These column stops are guided in slots in the
 bar 15 and are pivoted upon a fulcrum wire 17
 (Figs. 1 and 4) which is secured in a longitudinal
 slot in the rear vertical face of stop bar 15. The 40
 column stops cooperate with a tooth 18a (Figs.
 1 and 2) formed in the end of the usual tabular
 lever 18 which is pivoted at 19 (Fig. 2) to a rela-
 tively fixed part of the framework whereby said
 lever is capable of a slight rocking movement in 45
 a counterclockwise direction (Fig. 2) to project
 the tooth 18a into the path of a set stop. Nor-
 mally, the stops occupy the position indicated
 by the foremost stop in Fig. 4, but when set to
 active position are rocked in a counterclockwise 50
 direction to the position indicated by the refer-
 ence numeral 16a in Figs. 1 to 5.

The tabular lever 18 is operated to place the
 lug 18a in the path of the set column stops desig-
 nated 16a by means of a cam unit like 19, Fig. 1, 55

which is connected by a link 20 to a bell crank 21 pivoted on rod 22. The bell crank 21 is connected by a link 23 to a lever 24 (see Fig. 2 also) pivoted at 25 to a bracket 26 secured to the rear rail 13. The upper end of this lever 24 has a tooth projecting into a slot (not shown) in the lever 18 whereby, when the link 23 is drawn to the left in Fig. 2, the lever 18 will be rocked in a counterclockwise direction a slight amount. At 10 the same time, by means not shown, the usual escapement dogs are released and the carriage is allowed to move freely under the influence of the spring drum 13 until a set stop 16a strikes the lug 18a to arrest the carriage in the proper 15 columnar position determined by the set stop. The cam unit 19 which operates the bell crank 21 is controlled by the usual tabular key 27 which, when depressed, causes a cam 19a forming part of the cam unit 19 to rotatably cooperate 20 with the power roller 28. This power roller continually rotates in the direction of the arrow (Fig. 1) whereby the tabular lever 18 is operated once upon each depression of key 27.

According to the present invention, improved 25 means are provided to set the column stops 16 in a position to engage the lug 18a whenever the lever 18 is operated as described above. One form of the stop setting means is disclosed in Figs. 1 to 5, inclusive. Figs. 3, 4, and 5 show on a large 30 scale the stops and the parts of the stop setting mechanism which cooperate with the stops. Secured to the top surface of a plate 30, which is utilized as a cover for certain portions of the mechanism located in the rear part of the machine, are brackets 31 on which is pivotally mounted a frame 32 resembling a bail. One of the brackets 31 has secured thereto a hub 31a through which passes a shaft 33 on which the frame 32 is loosely pivotally mounted, the shaft 33 being secured against rotation by means of a set screw 31b in the hub 31a. The frame 32 is urged in a clockwise direction (Fig. 4) by means of a torsion spring 34, one end of which is passed through a hole drilled diametrically of shaft 33, while the other end is hooked around one arm of the frame 32. The frame 32 is also provided with a bent-over lug 32a carrying an adjustable stop screw 32b which cooperates with the under surface of the plate 31 to limit clockwise rotation 45 (Fig. 4) of the frame 32.

Slidably mounted on the frame 32 by means of studs 35 is the stop setting head comprising a T-shaped member 36. The T-shaped member 36 is slidable in a direction parallel with the movement of the carriage whereby under certain circumstances said member may be moved by the carriage as will be made clear hereinafter. Normally the T-shaped member 36 is held in a central position by means of two opposed springs 50 37 which are anchored to a lug formed in the T-shaped member and two lugs formed in the cross bar of frame 32.

The T-shaped member is formed with two lugs 55 36c and 36b. Normally the springs 37 hold the member 36 in such a position that, when the frame 32 is rocked in a counterclockwise direction (Fig. 4), lug 36a will rock one of the stops 16 to the position designated by the reference numeral 16c. During a subsequent tabulating 60 operation initiated by the depression of the key 27, the set stop 16a will engage tooth 18a and the carriage will be arrested in a position corresponding to the one which it had when the stop 16a was projected to active position. The stop screw 70 32b is adjusted so that normally the frame 32

occupies the position shown in Figs. 3 and 4 in which there is a small clearance between the end of the lug 36a and the unset stops, so as to permit the carriage to move freely without interference between the lug 36a and any of the unset stops 16. 5

For the purpose of operating the setting head 36 to set a selected stop 16 to active position, there is provided an operating member in the form of an arm 38 which is rigidly secured to a shaft 39 journaled in lugs 30a formed in plate 30. 10 The upper end of the arm 38 has a tooth 38b confronting the end of the lug 36b. It is evident from Figs. 3 and 4 that the rocking of arm 38 in a counterclockwise direction will cause the frame 32 to be similarly rocked by engagement of the 15 tooth 38b with the tooth 36b. Thus, the T-shaped member 36 acts as an interposer between the arm 38 and any stop 16 that may be in position to be set.

The arm 38 is operated by means of a stop 20 setting key 40 (Figs. 1 and 2) which is pivotally mounted on a fixed bracket 41 and is connected by link 42 to an arm 43 secured to the shaft 39. Thus, whenever the key 40 is depressed, the frame 32 will be rocked in a counterclockwise direction, 25 Figs. 1 and 4.

It may happen that after the key 40 has been depressed and the lug 36a on member 36 is still between two unset stops the carriage may be moved. For example, in depressing the stop setting key 40, the operator might also accidentally depress the usual carriage return key (not shown). Obviously, if the carriage begins to move while the stop setting head is between two unset stops, damage to some part, such as the head 36 or the column stops might result, or the carriage return tape might break. Owing to the fact that there is a very limited space between the stops 16, it is not possible to make the tooth 18a strong enough to stand such abuse. 40

If it should happen that the carriage starts to move while a stop is being set, one of the unset stops adjacent the one which is being set will engage the side of the lug 36a and cause the stop setting head 36 to travel with the carriage against the tension of one or the other of springs 37. 45 After the carriage moves a little less than a letter space, the lug 36b will clear the end of the lug 38b and permit spring 34 to rock the frame 32 back to the position of Fig. 4. Fig. 5 shows the 50 position of the head 36 after this has occurred and, with the stop setting key still held depressed, it will be seen that the spring 34 has rocked the frame 32 to completely withdraw the tooth 36a of head 36 from between the unset stops 16 where- 55 by the carriage can now move freely without interference with any part of the stop setting mechanism.

Thus, it is impossible to damage either the stops 16 or the stop setting mechanism or break 60 the carriage return tape since the springs 37 offer practically no response to the movement of the head 36 by the carriage and are provided purely for the purpose of holding the head 36 in a central position. Obviously, these springs can 65 not be stretched to an extent sufficient to permanently deform them because, before either of them has been stretched to any material extent, the lug 36b will clear the lug 38a and further stretching will be rendered impossible by virtue 70 of disengagement of the lug 36a from the unset stop 16.

When the stop setting key 40 is released, a spring 44 coiled around a shaft 39 and engaging the arm 43 rocks the arm 38 back to the position 75

of Figs. 3 and 4, permitting the tensioned spring 31 to restore the stop setting head 36 to the position of Fig. 3.

The mechanism shown in Figs. 1 to 5 has the advantage of disengaging the stop setting head from the stops 16 very quickly, it being effective in slightly less than one letter space movement of the carriage. The actual amount of movement of the carriage required for disengagement of the head 36 from the stops is dependent upon the relative thickness of the lugs 36b and 38a. Thus, by making either of the lugs 36b, 38a very thin, the disengagement of the head 36 from the stops 16 can be effected with considerably less than a letter space movement of the carriage. However, there is a practical limit to doing this as the parts must have the necessary mechanical strength. Conversely, the lugs 36b, 38a may be made thicker to require a longer movement of the carriage before disengagement of the setting head takes place.

The construction shown in Figs. 1 to 5 has the disadvantage in that it depends upon the spring 34 to withdraw the stop setting head 36 from between the stops. Obviously, if the spring 34 broke, it is possible that in consequence of the friction between the side of an unset stop and the lug 36a, the stop setting head and the frame 32 might be held against restoration to the position of Fig. 4, in which case the carriage would move the head 36 until further movement of the head is prevented by the screws 35 after which the carriage would be blocked from further movement. Since the carriage would be permitted to acquire some momentum before the screws 35 finally stop further movement of the carriage, the tendency to breakage of the head would be greater in consequence of the greater shock with which the carriage would be stopped. Accordingly, in Figs. 6, 7, and 8, there is shown a form of the mechanism in which the movement of the carriage is utilized to cause the stop setting head 36 to be positively cammed from between the unset stops 16 before the carriage has moved any appreciable amount.

In Figs. 6 and 7 the stop setting head consists of an arm 45 having a toothed portion 45a adapted to engage the unset stops 16 and project them to the position 16a. This arm 45 is integral with a hub 46 which is rotatably and slidably mounted upon a shaft 47. This shaft 47 is supported by brackets 31a secured to the underside of the cover plate 30. The shaft 47 is prevented from moving longitudinally by means of collars 47a. Springs 48 interposed between the hub 46 and the collars 47a hold arm 45 in central position.

Also secured to the hub 46 is an arm 49 on which is pivotally mounted, near its midpoint, a lever 50. The left-hand arm (Fig. 7) of lever 50 projects into a cam slot 51a formed in a block 51 secured to the top surface of the plate 30. The right-hand arm of the lever 50 has a hole in which loosely slides a pin 52 in the left-hand end of a link 53, which is pivotally connected, at its right-hand end, to an operating member in the form of an arm 54 secured to shaft 39. The right-hand arm of lever 50 also has a bent-over lug 50a projecting through the plane of the link 53. A spring 55, anchored to the lever 50 and to an ear (not shown) formed in the plate 30, tends to rock the lever 50 in a clockwise direction

so that normally the lug 50a presses on the top edge of the link 53.

The right-hand arm of lever 50 and the link 53 comprise a toggle and the lug 50a is so disposed that under normal conditions the common pivot pin 52 of the toggle is a little below a line drawn through the pivot of link 53 to arm 54 and the pivot for lever 50 whereby, as arm 54 is rocked counterclockwise in Fig. 7, the arm 49 and hence arm 45 will be similarly rocked, the spring 55 and lug 50a preventing bending of the toggle. Thus ordinarily the link 53 and the arm of lever 50 act like a rigid link interconnecting arms 49 and 54.

The arm 45 is provided with a bent-over lug 45a having a stop screw 56 which engages the top surface of the plate 30 to limit clockwise movement of the arms 45 and 49. A spring 57, connected to arm 45 and a pin on the plate 30, normally holds the arm 45 in the position of Fig. 7 with lug 45a clear of the unset stop 16.

With reference to Fig. 8, it will be noted that the left-hand arm of lever 50 normally occupies a position close to the deepest portion of the cam slot 51a. When the shaft 39 is rocked in a counterclockwise direction to set a selected stop the left-hand arm of lever 50 is moved toward the block 51 and slightly upward until the lever practically touches the deepest portion of the cam slot 51a. If, while the stop setting key is held depressed, the carriage should be moved, the contact of the unset stop on one side or the other of the tooth 45a, according to the direction in which the carriage moves, will cause the arm 45, hub 46, and arm 49 to move longitudinally of shaft 47 against the tension of one of the springs 48. This will cause the lever 50 to be moved bodily in the same direction; this movement being permitted by the length of the lug 50a and the sliding connection between the pin 52 and the right-hand arm of lever 50. However, the shape of the cam slot 51a is such that, when this movement takes place, the lever 50 will be cammed in a counterclockwise direction (Fig. 7) against the tension of the spring 55, thereby bending the toggle comprising link 53 in the right-hand arm of lever 50 and moving arm 45 back to the position of Fig. 7. The spring 57 is considerably superior in tension to the spring 55 and, once the pin 52 has moved a small amount above a line drawn through the pivots for link 53 to arm 54 and for lever 50, the spring 57 will take effect to assist cam 51a in bending the toggle sufficiently to move the lever 45 to the position of Fig. 7, notwithstanding the fact that arm 54 may still be held in operative position by the operator holding down the stop setting key 40. Thus, the arm 45 is positively forced out from between the unset stops and remains in the position of Figs. 6 and 7.

As soon as the stop setting key is released, the arm 45 remains immovable since it has already moved as far in a clockwise direction as it can and is being held in this position by the spring 57. The result is that the toggle comprising the members 50, 52 will be restored to the position of Fig. 7, by the combined action of spring 55 and the spring 44 which restores the stop setting key to normal position. The spring 55 may be made very weak as its only purpose is to insure that the toggle will be pulled back to the locking position when the stop setting key is released which requires a relatively small force.

In the form of the invention disclosed in Figs. 1 to 5, as soon as the stop setting head 36 is withdrawn from between the stops, the spring 34 holds the head in the position of Fig. 5 and prevents it from being drawn back to the central position by the active spring 37. As long as the stop setting key 40 is held depressed, the head will remain in this position and will be restored to the central position only when the stop setting key is released. Thus it is impossible for the stop setting head to re-engage the unset stops once it has been withdrawn. In the form of the invention shown in Figs. 6 to 8, the stop setting head, which in this case comprises the arm 45, is free to be returned to the central position by the compressed spring 48. The result is that the head 45 returns to the central position as soon as it is moved clear of the unset stops; however, owing to the spring 57 being superior to the spring 55, the head is held in the normal position clear of the stops and cannot be again moved to engage an unset stop until the stop setting key 40 has been released. Thus in the form of the invention shown in Figs. 6, 7, and 8 it is impossible to re-engage the head 45 after it has once been disengaged from the unset stops. It is quite possible, however, that the spring 57 might become weak or break so as to permit the head 45 to become drawn back between the unset stops in consequence of the tension of spring 55. This will do no harm, however, since, with continued movement of the carriage, the head will be immediately forced out from between the unset stops by the cam 51a and the only effect produced might be a continuous reciprocation and oscillation of the head on its shaft 47. The cam 51a is so shaped that it will always move the head 45 out from between the stops independently of the spring. Normally both the spring 40 and the cam work together so closely that it might be difficult to determine which of these elements is most responsible for the withdrawal of the head from between the stops. Thus the cam 51a acts not only as a controlling member for rendering the withdrawing means effective, but it also acts by itself as a withdrawing means in the event of sticking of the parts or breakage of the spring 57.

While there has been shown and described and 50 pointed out the fundamental novel features of the invention as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

60 What is claimed is:

1. In combination with the carriage of a typewriting machine, column stops movably mounted on the carriage so as to be settable from an inactive to an active position, a stop setting key, a stop setting head, means operated by depression of said key for actuating the stop setting head to set a selected stop in active position, and means controlled by movement of the carriage to withdraw the stop setting head from between the stops independently of the depressed key.
2. In combination with the carriage of a typewriting machine, column stops movably mounted on the carriage, means cooperating with the stops to project them to an operative position

from an inoperative position, a stop setting key, means operated by the stop setting key for operating the stop setting means, and means operated by movement of the carriage to positively restore the stop setting means in the event the carriage moves while the stop setting key is depressed.

3. In combination with the carriage of a typewriting machine, a series of column stops for defining columnar positions of the carriage and movable from an active to an inactive position; a stop setting head, said stop setting head and said column stops being relatively movable to select a stop for projection to an active position, means to mount the stop setting head for movement into engagement with the selected stop to project it to active position, means to mount the stop setting head for movement in the same direction as the movement to select the stops, a stop setting key, means controlled by the stop setting key for operating the setting head to set a stop to active position; and means operative, when the stop setting key is held depressed and the relative selecting movement takes place, to automatically withdraw the stop setting head from between the unset stops.

4. In combination with the carriage of a typewriting machine, a stop bar mounted in the carriage, column stops movably mounted on the stop bar so as to be settable from an inactive to an active position, a stop setting head for cooperating with a selected stop to set same to active position, means to movably mount the stop setting head for movement transversely of the stop bar to set the stop to active position, means to movably mount the stop setting head for movement in either direction parallel with the movement of the carriage, a stop setting key, means operated by the stop setting key for actuating the stop setting head in a direction transversely to the stop bar, and means rendered effective by the second named movement of the stop setting head and operative, upon a predetermined movement of the carriage while the stop setting key is held depressed with the stop setting head between the unset stops, to withdraw the stop setting head from between the stops to permit the carriage to move freely without further obstruction by the stop setting head.

5. In combination with a stop bar having a plurality of column stops movable from an inactive to an active position, a stop setting head; means to movably mount the stop setting head for movement transversely of the stop bar to set a stop to active position, said mounting means also permitting said stop setting head to move longitudinally of the stop bar; means to actuate the stop setting head to move said head transversely of the stop bar, and means controlled by said longitudinal movement of the head to cause the stop setting head to become disengaged from the stops when the stop bar and setting head tend to move relative to each other longitudinally of the stop bar.

6. In a stop setting tabulating mechanism for typewriter carriages, a row of column stops, a setting member movable into engagement with a selected column stop to set same to operative position, a stop setting key, means controlled by said key for actuating said member, and means rendered effective by movement of the carriage for automatically disabling the actuating means and withdrawing said member from engagement with the stop when the carriage moves.

7. In a stop setting mechanism, in combination with a row of column stops, each settable

25

30

35

40

45

50

55

60

65

70

75

from an inactive to an active position; a stop setting member movable transversely of the row of stops to set a selected stop to active position, said stop setting member and said row of stops being movable relative to each other longitudinally of the row of stops to select the stop to be set, said stop setting member being further movable parallel with the selecting movement in either direction from a central operating position from which the column stops are set; an operating member for said stop setting member cooperating with a portion of the stop setting member to operate said member when it is in its central position, said stop setting member being disengageable from its operating member when the stop setting member moves in either direction parallel with the selecting movement and away from the central position; means to hold the stop setting member in its central position, and means operative when the stop setting member is moved parallel with the row of stops to move the stop setting member out of engagement with the stops and out of operative relationship with the operating member.

25 8. In a stop setting mechanism, in combination with a row of column stops; a stop setting member cooperating therewith and movable transversely of the row of stops to set a selected stop, said stop setting member and said row of stops being movable relative to each other in a direction parallel with a row of stops to select the stop to be set, said stop setting member being movable with the row of stops when said member is projecting a stop to active position by engagement with the side of an adjacent unset stop in the event that the selecting movement takes place while a stop is being set to active position; an operating member with which said stop setting member normally has an operating relationship; means for maintaining the stop setting member in its operating relationship with the operating member, said means being constructed and arranged to enable the stop setting member to move in either direction parallel with the selecting movement out of operating relationship with said member upon a movement of the stop setting member with the row of stops; and means operative to withdraw the stop setting member from between the stops when the stop setting member is moved out of operating relationship with the operating member.

9. In a stop setting mechanism, the combination of a row of column stops, each movable from an inactive to an active position; a stop setting member movable transversely of the row of stops to set a selected stop to active position, said member and said row of stops being movable relative to each other longitudinally of the row of stops to select the stop to be set; an operating member for the stop setting member operative to move the stop setting member from a normal inactive position transversely of the row of stops to set the selected stop; and means operative while said operating member is in operated position for moving the stop setting member back to its normal position and counter to the direction in which it is moved by the operating member, said means becoming operative only in the event that the selecting movement takes place while the stop setting member is away from its normal position, said means including means responsive to the selecting movement for positively forcing the stop setting member out of engagement with the stops.

75 10. In a stop setting mechanism, the combina-

tion with a row of column stops, each movable from an inactive to an active position, a member for setting a selected stop to active position, said member and said row of column stops being movable relative to each other longitudinally of said row of stops to select the stop to be set, said member being slidably mounted for movement parallel with the selecting movement so as to be capable of movement with the column stops longitudinally of said row, means to hold said member in a central position in which the member is movable transversely of the stops to select the selected stop, said means permitting said member to slide in either direction away from the central position; means cooperating with said member for moving it transversely of the row of stops while in the central position and disengageable from said member when the latter is moved away from the central position in either direction, and means operative to move said member transversely of the row of stops and counter to the movement to set the stops when the selecting movement takes place while said member is setting a stop.

11. In a stop setting mechanism, the combination with a row of column stops, stop setting means pivotally and slidably mounted for movement transversely of the stops to set a stop to active position and for movement at right angles to the stop setting movement to permit the stop setting means to travel with the column stops, an operating member for the stop setting means, and means operatively connecting said member with the stop setting means and normally effective to enable the operating member to move the stop setting means transversely of the row of stops to select a selected stop, said connecting means being responsive to movement of the row of stops while the stop setting means is in operated position to retract the stop setting means from engagement with the stops and to hold said stop setting means in retracted position notwithstanding the fact that the operating means remains in operated position.

12. In combination with the carriage, a row of column stops for determining different positions of the carriage, said column stops being movable from an inactive position to an active position; means cooperating with the stops to project them to the active position, said last named means and column stops being relatively movable longitudinally of the row of column stops to select a stop for projection to the active position; operating means for the stop moving means, and means controlled by the movement of the carriage to automatically restore the stop projecting means independently of the operating means in the event the carriage moves after the operating means has been operated.

13. In combination with a stop bar and a series of column stops mounted on the stop bar for movement transversely of the bar from an inactive to an active position; a stop setting arm, said arm and said stop bar being movable relative to each other longitudinally of the stop bar to select a stop for movement to the active position; means to mount said arm for movement transversely of the stop bar to set the selected stop to active position and for movement longitudinally of the stop bar in either direction to enable said arm and said stop bar to move together longitudinally of the stop bar, a stop setting key, an operating member for said arm controlled by the stop setting key, a toggle interconnecting the operating member and the stop setting arm, means to hold

- the toggle in a straightened position whereby said toggle normally acts like a rigid link to enable movement to be communicated from said member to the stop setting arm when the key is operated 5 whereby the selected stop may be set to active position upon a depression of said key, and means operative when the stop bar and said arm move together in a direction parallel with the stop bar to bend the toggle and thereby enable said stop setting arm to be withdrawn from engagement with the column stops independently of the position of said member.
14. In a stop setting mechanism, the combination of a row of column stops, each movable from 15 an inactive to an active position; a setting member for moving the stops from the inactive to the active position, said member and said row of stops being movable relative to each other in a direction longitudinal of the row of stops to select the 20 stop to be moved to active position; means to operate the stop setting member, means to mount said setting member for movement relative to the operating means in a direction parallel with the row of stops whereby said member and said row 25 of stops may move together longitudinally of the row of stops when said stop setting member has been moved into the space occupied by the selected stop when in the inactive position, said stop setting member, when moved relative to the operating means in the manner aforesaid, being withdrawn from cooperative relationship with the operating means; and means operative, when the aforesaid movement of the stop setting member and row of stops takes place and the operating 30 means remains in operating position, to withdraw said member from the space occupied by the selected stop when in its inactive position.
15. In a stop setting mechanism, the combination of a row of column stops, each movable from 40 an inactive to an active position; a setting member for moving the stops from the inactive to the active position, said member and said row of stops being movable relative to each other in a direction longitudinally of the row of stops to select the stop to be moved to active position; means to operate the stop setting member, means to mount said setting member for movement relative to the operating means in a direction parallel with the row of stops whereby said member and 45 said row of stops may move together when said stop setting member has been moved into the space occupied by the selected stop when the stop is in the inactive position, said stop setting member, when moved relative to the operating means in the manner aforesaid, being withdrawn from cooperative relationship with the operating means; and means operative, when the aforesaid movement of the stop setting member and row of stops takes place and the operating 50 means remains in operating position, to withdraw said member from the space occupied by the selected stop when in its inactive position.
16. In a stop setting tabulating mechanism, a row of column stops, each movable from an inactive to an active position; a member movable transversely of the row of column stops to move a selected column stop from the inactive to the active position, said row of column stops and said member being movable relative to each other 55 longitudinally of the row of column stops to select the stop to be moved to active position; operating means for said member; and means for automatically withdrawing said member from the space occupied by the selected stop when in the inactive position, said means being rendered 60 effective when said operating means is in operated position and the relative selecting movement occurs.
17. In a stop setting mechanism, a row of column stops, each movable from an inactive to an active position; a member for moving said stops to the active position, means to movably mount said member to enable the row of column stops and said member to move together parallel with said row, operating means for said member, 10 means to enable said operating means to operate said member, and means controlled by movement of the stop moving member and operative, when the column stops and said member move together with the operating means in operated position, to 15 disengage said member from the stops and render temporarily inactive the enabling means between the operating means and said member.
18. In combination with a carriage, a row of column stops associated with the carriage for 20 defining columnar positions of the carriage, said column stops being movable from an inactive position to an active position; a member for moving the column stops to the active position, said member and said column stops being movable 25 relative to each other longitudinally of the row of stops to select a stop for movement to the active position; operating means for said member, said member being normally in a position to be operated by said operating means; and means 30 to movably mount said member to enable said member and said column stops to move together a predetermined extent to effect a disconnection between the operating means and said member in the event the carriage moves while the operating 35 means is in operating position.
19. In combination with a carriage, a row of column stops, means to movably mount the column stops to enable each stop to be moved from an inactive position to an active position defining 40 a columnar position of the carriage; means movable into engagement with the stops to project the stops to the active position, said projecting means and said row of stops being movable relative to each other in a direction parallel to the 45 row of stops to select a stop for movement to the active position, said projecting means being engageable with and moved by stops which are in the inactive position when the carriage moves while the projecting means is projecting a stop 50 to the active position; operating means for the projecting means, and means controlled by the movement of the projecting means by said stops for automatically withdrawing the projecting means from between the inactive stops to permit 55 the carriage to move freely in the event the carriage moves while the operating means is operating the projecting means.
20. In combination with a carriage, a stop bar having a series of column stops movably mounted 60 on said bar so as to be actuatable from an inactive position to an active position, a stop setting key, a member operated by the stop setting key, a stop setting head movable transversely of the stop bar to set a selected stop, means to 65 movably mount said setting head to enable the head to be moved parallel with the stop bar and transversely of the key operated member in the event that the carriage moves while said head is setting a selective stop to the active position, 70 means between the setting head and the key operated member for causing the setting head to move a selected stop to the active position when the key is depressed, said means being capable of being rendered inoperative when the 75

setting head moves parallel with the stop bar, and means, rendered effective by the transverse movement of the setting head, to withdraw the setting head when the head moves parallel with 5 the row of stops.

21. In a stop setting tabulating mechanism a row of column stops, each movable from an inactive to an active position; a stop setting element movable transversely of said row of stops 10 to set a selective stop to active position and movable parallel with the row of stops, means to operate the stop setting element, and means cooperating with both the stop setting element and its operating means for effecting a withdrawal 15 of the stop setting element from between the stops, said means being rendered effective to withdraw the setting element by the movement of the latter parallel with the row of stops.

22. In a stop setting mechanism, the combination of a row of column stops, each movable from an inactive to an active position; a stop setting member movable transversely of the row of stops to set a selected stop to active position, said member and said row of stops being movable 25 relative to each other longitudinal of the row of stops to select the stop to be set, said selected member also being movable with the row of stops when the stop setting member is setting a stop to active position and said row of stops is moved 30 longitudinally; an operating member for the stop setting member; means to enable the operating member to move the stop setting member, from a normal inactive position, transversely of the row of stops, to set a selected stop; and means 35 rendered effective by movement of the stop setting member longitudinal of the row of stops by movement of said stops to move the stop setting member back to its normal position in the event that the selecting movement takes place while 40 the stop setting member is away from its normal position.

23. In combination with a carriage, a counterstop, a row of column stops for determining different columnar positions at the carriage, said 45 stops being movable from an active to an inactive position to coact with the counterstop and arrest the carriage in the columnar positions defined by the column stops; an element movable transversely of the row of stops to set 50 a stop to the active position, said element being slidably mounted for movement with the carriage in a direction parallel with the row of stops, means to operate said element, and means rendered effective by the sliding movement of said 55 element parallel with the row of stops for ren-

dering the operating means incapable of holding the stop setting element in operated position.

24. In a machine of the class described, the combination with a carriage, a counterstop, a support; a series of stops disposed along the support in a row, said stops being movable from an inactive to an active position to cooperate with the counterstop to arrest the carriage in columnar positions defined by the stops which have been set to the active position; a stop setting 10 element movable transversely of the row of stops to set a stop to the active position; an operating element for the stop setting element, said operating element being movable transversely of the row of stops to move the stop setting element to 15 set a selected stop to the active position, said elements being movable relative to each other at right angles to the stop setting movement, said relative movement being effected by movement of one of said elements by the carriage, and 20 means rendered effective by said relative movement for preventing an operation of the setting elements by the operating element until the operating element is restored to its initial position. 25

25. In combination with a carriage, a row of column stops movable from an inactive to an active position, mechanism for setting a selected column stop in the active position including a disruptible operating train and an element co- 30 acting directly with the column stop to move it to the active position when the operating means is operated, and means rendered effective by a movement of the carriage for disrupting the operating train. 35

26. In combination with a carriage, a series of column stops, said column stops being movable from an active to an inactive position, an operating member and a coacting operated member, said members being relatively movable; means 40 to enable the operated member to project a stop to the active position, means to actuate the operated member, said operating member and the operated member being normally coactive to cause a stop to be projected to the active position whenever the actuating means is effective, and means rendered effective by the relative movement between said members to prevent one member from being operated by the other unless the actuating means and the operating members 45 are restored to their initial position, said relative movement being effected by movement of the carriage while a stop is being projected to the active position. 50
